ELECTRO-MECHANICAL VOICE TRANSDUCER

Jerry O'Brien, 33 Pamrapo Ave.,
Jersey City, N.J. 07305

Filed Mar. 25, 1974, Ser. No. 454,221

Term of patent 14 years

Int. Cl. D14—03

U.S. Cl. D26—14 L

Fig. 1

Fig. 4

Fig. 2

Fig. 3

FIG. 1 is a top perspective view of an electro-mechanical voice transducer, showing my new design;

FIG. 2 is a top plan view thereof;

FIG. 3 is a side elevation thereof; and

FIG. 4 is a bottom plan view thereof.

I claim:

The ornamental design for an electro-mechanical voice transducer, as shown and described.
